Motors Corporation, Detroit, Mich., a corpora-
tion of Delaware

Application February 17, 1942, Serial No. 431,253

4 Claims. (Cl. 153—65)

This invention relates to devices for coiling tubing as it moves horizontally from the end of a continuous tube mill.

An object of the present invention is to provide a coiling device which provides means for forming the tubing into a helical spiral which is received by a support and which permits the severing of a number of turns and removal thereof without stopping the coiling device. To accomplish this object, I provide a pair of power driven feed rolls between which the tubing passes, a bending roll which engages the tubing to cause it to be bent into a turn of the spiral, a guiding plate having a warped surface engaging the tubing as it is being formed into a turn of the spiral to determine the pitch of the spiral, and a rotatable support which receives the spiral turns of the tubing after they are formed. The tubing may be cut at a point adjacent the guiding plate so that a coil of tubing comprising a number of spiral turns may be removed without stopping the coiling device.

Further objects and advantages of the present invention will be apparent from the following description, reference being had to the accompanying drawings wherein preferred embodiments of the present invention is clearly shown.

In the drawings:

Fig. 1 is a front view of a coiling device embodying one form of the present invention. The part in section is on the line 1—1 of Fig. 4.

Figs. 2 and 3 are fragmentary views taken in the direction of the arrows 2 and 3, respectively, of Fig. 1.

Fig. 4 is a side view of the machine shown in Fig. 1.

Fig. 5 is a sectional view on the line 5—5 of Fig. 1.

Fig. 6 is a plan view of another coiling device embodying the present invention.

Fig. 7 is a side view of the device shown in Fig. 6, taken in the direction of arrow 7 of Fig. 6.

Figs. 8 and 9 are sectional views on lines 8—8 and 9—9 respectively of Fig. 6.

Referring to Figs. 1 through 5, a pedestal 20 provides bearing bushings 21 and 22 (Fig. 5) for supporting a shaft 23 connected with a gear 24 driven by gear 25 driven by a shaft 26 (Figs. 3 and 4) which is driven by an electric motor not shown. The shaft 26 is supported by bearing brackets 26x, 27 and 28, supported by the pedestal 20. Brackets 27 and 28 support a non-rotatable tube 30 surrounding shaft 26. Tube 30 provides a bearing for a clamp-hub 31 tightened around said sleeve 30 by screws 32. Hub 31 is connected by arms 34 with a tubular portion 35 carrying a bearing liner 36 supporting a shaft 37 carrying a gear 38 and a grooved roller 39. Gear 38 meshes with an idle gear 40 meshing with gear 41 connected with shaft 26, said idle gear being mounted

on a stub shaft 42 attached to a lug 43 integral with the tube 35. Thus the shaft 26 drives gear 24. Gear 24 is connected by pins 45 with a roller 46. By adjusting the shaft 31 and the supporting tube 35 about the sleeve 30, and clamping the clamp hub 31 about the sleeve 30, the roller 39 is caused to bear with a desired pressure against the tubing T which is pressed against the roller 46. Before passing between rollers 39 and 46, 10 the tubing T passes in a substantially horizontal direction toward the left, Fig. 1, from a continuous tube-forming mill.

The tubing T passes between the rolls 39 and 46 and then under a grooved guide wheel 50 rotatable 15 with a shaft 51 journaled in a bearing bushing 52 pressed into an arm 53 having a clamping hub 54 encircling a stub shaft 55 having a shank 56 passing through an arcuate slot 57 in a bracket 58 attached to the pedestal 20. The center curvature of slot 57 is the center of shaft 23. After the position of shank 56 within the slot 57 has been determined, it is fixed in that position by the tightening of a nut 59 thereby causing the shoulder 55a of the stub shaft to bear against the bracket 58. The arm 53 can be rotated about the stub shaft 55 when the clamp arm is loosened. After the wheel 50 has been brought into the desired position, screws 54a are tightened in order to tighten the clamp arm about the stub shaft 30 55.

The guide wheel 50 is so located with respect to the wheel 39, that the tubing T is caused to take a circular path which causes the tubing to form itself into spiral loops which are supported 35 by a drum 60 having its right end approximately flush with the periphery of the wheel 46 and having at its left end a flange 61. Drum 60 is connected by spider plates 62 with a hub 63 carrying bearing bushings 64 by which the drum is 40 loosely journaled on shaft 23 and is confined by thrust bearings 65 and 66 the former bearing against the hub of the wheel 46 and the latter being confined by a nut 67 on the left end of shaft 23. After tube T passes from the tube-mill, it 45 passes behind a guide plate 70 and then between the rolls 39 and 46 and then as it passes under the guide wheel 50 it passes in front of a guide plate 71. The plates 70 and 71 are provided with arcuate recesses or orifices as at 72 in order 50 to clear the wheel 46. The plate 71 is supported by the pedestal 20 by suitable brackets, one of which is shown at 73, and the plate 70 is supported by pedestal 20 by brackets similar to brackets 73. As the tubing T passes toward the 55 left from the rollers 46 and 39, it is caused to make a spiral path due to the warped surface of helical formation provided by the guide plate 71. Plate 71 determines the pitch of the spiral turns. As the tube is formed into spiral turns, its free end 60 approaches the flange 61 of the drum 60. If it is

desired to prevent any of the turns of the tubing from leaving the drum 60, a metallic spring clamp such as a metal clothespin is snapped on the end turns of the spiral coil of tubing T in order to retain the tubing upon the drum. After a certain number of turns of tubing have been formed around the drum, the tubing coil may be severed from the tubing position then between the rolls 39 and 46 so that the tubing coil may be removed from the drum to leave room for other spiral turns which are being spirally formed around it.

In the form shown in Figs. 6 through 9, the tubing T is coiled into a vertically disposed helix. Pedestal 100 supported by a base 101 supports a frame 102 carrying bearings 103 for a shaft 104 driven by an electric motor supported on a bracket (not shown) adapted to be supported on the frame surface 102a. Shaft 104 drives gear 105 meshing with gear 106 fixed to shaft 107 journaled in bearing 108 carried by frame 102. Shafts 104 and 107 drive, respectively, rolls 109 and 110 which are grooved to receive the tube T which is gripped between them. Gear 105 meshes also with a wide faced gear 111 journaled on a screw 112 (Fig. 9) threaded into one of two swinging arms 113 which are journaled on a sleeve 114 carried by bracket 102 and directly supporting the bearings 103 of the shaft 104. The two arms 113 merge into a tubular part 115 supporting bearings 116 upon which a shaft 117 is journaled. Shaft 117 carries gear 118 meshing with gear 111 and shaft 117 drives grooved wheel 119. Wheel 119 which is directly under gear 118 in Figs. 6 and 7 bears against the tube T after it emerges from between the wheels 109 and 110 and causes the tubing T which moves in the direction of arrow 120 to move in a circular path. The location of the wheel 119 is adjusted by the turning of a turn buckle 121 having its ends tapped respectively for right and left hand threads for receiving similarly threaded rods 122 and 123 connected at 124 and 125, respectively, with the frame 102 and the lower one of the arms 113.

During its circular movement the tubing T gravitates upon a guide plate 130 having a spiral bottom surface 131 and a flange 132. Plate 130 is supported by bars 133 and 134, respectively, extending from screws 135 and 136, respectively, between which the bar ends are clamped in adjusted position along the screw 135 or 136. These screws are supported, respectively, by brackets 139 and 140 mounted on opposite sides of the pedestal 100.

The tubes T descend in spiral fashion upon the bottom wall 141 of a tray having a cylindrical side wall comprising a fixed part 142 and movable parts 143 and 144 hinged respectively at 145 and 146 (Fig. 6) and latched together by a latch lever 147 (Fig. 7) pivoted at 148 on a bracket 149 attached to part 144. Lever 147 has a hook 150 for engaging a pin 151 carried by a bracket 152 attached to part 143. The bottom wall 141 of the tray is supported by a pad 155 (Fig. 8) attached to the upper end of the shaft 156 journaled in bearing bushing 157 carried by a bracket 158 carrying also a step bearing 159 for supporting the shaft.

In both forms of the invention, I provide a pair of power driven feed rollers between which the tubing passes from a continuous tube forming mill, a wheel engaging the tubing to bind it into arcuate form, a guide plate having a warped

surface engaged by the tubing to guide the tubing in a helical path, and a rotatable support for receiving the helical turns of the tubing.

While the embodiments of the present invention as herein disclosed, constitutes a preferred form, it is to be understood that other forms might be adopted, all coming within the scope of the claims which follow.

What is claimed is as follows:

1. A tube coiling device comprising a pair of power driven feed rolls between which the tubing passes from a supply source, said rolls being rotatably supported with their axes vertical, a wheel rotatably supported with its axis vertical and engaging the tubing after it passes between the feed rolls for causing the tubing to be bent into arcuate formation, a guide plate upon which the tubing gravitates and having a warped surface engaged by the tubing to guide the tubing in a helical path, and a rotatable pan mounted with its axis vertical and coinciding substantially with the axis of the helix of the tubing and having a bottom wall supporting helical turns of the tubing.

2. A tube coiling device comprising means for receiving tubing moving in a substantially straight path and for causing it to move in a helical path with the axis of the helix vertical, and a rotatable pan supported with its axis vertical and coinciding substantially with the axis of the tubing-helix for directly engaging the lower end turn of the tubing-helix as the tubing moves in a helical-spiral path.

3. A stock coiling device comprising, a pair of power driven rolls between which stock passes from a supply source; a plate for changing the direction of travel of the stock as it leaves the feed rolls; a wheel engaging the stock after it starts to change its direction of travel for causing the stock to be bent into arcuate formation from which a helix is formed; a rotatable support for receiving the helical turns of the stock; and means to determine the curvature and size of the helix, said means comprising a relatively stationary member having an arcuate slot concentric with the axis of the rotatable support, an arm carrying the wheel at one end and having its other end pivoted on a shaft adjustable to various positions within the arcuate slot; means for clamping the arm on the shaft; and means for clamping the shaft within the arcuate slot.

4. A stock coiling device comprising, a pair of power driven rolls between which stock passes from a supply source; a plate for changing the direction of travel of the stock as it leaves the feed rolls, a wheel engaging the stock after it starts to change its direction of travel for causing the stock to be bent into arcuate formation from which a helix is formed; a rotatable support for receiving the helical turns of the stock; means to change the relation of the wheel relative to the rolls whereby the curvature and consequently the size of the helix may be changed, said means comprising a relative stationary member having an elongated slot, an arm carrying the wheel at one end and having its other end pivoted on one end of a shaft and said shaft having the other end projecting through the slot and capable of being moved to various positions along the slot; means for clamping the arm to the shaft; and means for clamping the shaft to the stationary member.
